LAMP SOCKET WITH SIDE SWITCHING
MECHANISMCarl Bramming, Anderson, Ind., assignor to The
Mantle Lamp Company of America, Chicago,
Ill., a corporation of Illinois

Application June 10, 1944, Serial No. 539,757

17 Claims. (Cl. 200—51.14)

1

This invention is an improved construction of socket for electric lamps, which includes switching mechanism mounted in the side of the socket construction for controlling the circuit to the lamp bulb mounted in the socket, as a result of which the over-all dimension of the socket construction axially thereof may be the minimum required for properly supporting the lamp bulb and effecting connection between the terminals of the socket, and the electric conductors used to supply current to the socket. Heretofore, switch sockets for lamp bulbs have been provided with switching mechanism of one kind or another in the base of the socket construction below the structure employed to receive and support the lamp bulb, which has resulted with said earlier constructions, in necessarily giving the socket construction an axial length sufficient to mount the lamp bulb and in addition, the extra axial length required to accommodate the switching mechanism. By the present invention, the additional axial length required to accommodate the switching mechanism is eliminated, since the switching mechanism is contained in the side of the socket construction, said switching mechanism being constructed to quite as effectively control the circuit to the lamp bulb as with switch sockets of the kinds heretofore used. The switching mechanism of the invention includes a switch knob or button outside of the enclosing shell of the socket construction, which button is movable to circuit-closing and opening positions, said buttons having connection with a cam of the switching mechanism, cooperating with a movable switch member of spring construction, so arranged relatively to the cam that movement of the button to its circuit-opening position imparts a substantially instantaneous movement of the switch member away from the switch contacts of the switching mechanism to open the circuit to the lamp bulb, and movement of said button to its circuit-closing position imparts a substantially instantaneous movement to said switch member to engage and electrically connect the contacts of the switching mechanism, to close the circuit to the lamp bulb. The construction of the invention has therefore all of the advantages of so called "snap" switches, without requiring the axial length of the socket construction to be greater than that required to support the lamp bulb and to accommodate the connections between the terminals of the socket with the electrical conductors employed to supply current to the socket.

More specifically, the invention provides a base

2
of insulating material having a tubular member of thin sheet metal to receive and make electrical contact with the metal sleeve on the base of the lamp bulb used with the socket, in a manner common in lamp socket constructions, the base being provided with a central contact for engaging the central end contact of the lamp bulb when the lamp bulb is held in place in the socket. The base of the socket construction is provided with a side recess in which a switching member of thin spring metal is mounted for free movement axially of the base, the switching member having surfaces cooperating with a cam movable relatively to the switching member axially of the base, by a button located outside of the shell of the socket construction, which button is movable axially of the base to operate said cam. The switching member and cam are constructed so that for the upper position of the button, when viewing the socket in an upright position with the lamp bulb extending above said socket construction, the switching member is pressed downwardly into firm engagement with the contacts of the switch structure, one of said switch contacts being electrically connected with one of the lamp bulb contacts, and the other of said switch contacts being connected with one of the socket terminals for connection with one of the electric supply conductors, the other of the socket terminals for connection with the supply conductors being electrically connected in the socket construction with the other of the lamp bulb contacts.

The socket construction not only reduces the axial height thereof to a minimum, but it accomplishes the results described by simple means which may be cheaply produced, without in any way interfering with the effectiveness of operation of the structure.

40 The objects of the invention are to produce a switch socket for use with electric lamp bulbs constructed as described and having the advantages set forth.

The invention will be best understood by reference to the accompanying drawings illustrating a preferred embodiment thereof, in which—

45 Fig. 1 shows the assembled socket construction in plan view,

Fig. 2 shows the structure of Fig. 1 in front elevation,

Fig. 3 is a sectional view of a part of the structure shown in Fig. 1, taken along the line 3—3 in Fig. 1,

Fig. 4 is a sectional view of the structure shown 50 in Fig. 1, taken along the line 4—4 in Fig. 1,

Fig. 5 is a left-hand side elevation of the structure shown in Fig. 1.

Fig. 6 is a right-hand side elevation of the structure shown in Fig. 1 with the switch button removed, this view being taken along the line 6—6 in Fig. 1.

Fig. 7 is a sectional view of a part of the structure shown in Fig. 1 taken along the line 7—7 in Fig. 1.

Fig. 8 is a sectional view of a part of the structure shown in Fig. 4 taken along the line 8—8 in Fig. 4.

Fig. 9 is a sectional view of a part of the structure shown in Fig. 4 taken along the line 9—9 in Fig. 4, and shows the switching mechanism in its circuit-closing position.

Fig. 10 is a view similar to Fig. 9 showing the cam of the switching mechanism in its position immediately before the switching member of the switching mechanism is snapped toward its circuit-opening position.

Fig. 11 is a view similar to Fig. 9 showing the switching mechanism in its circuit-opening position.

Fig. 12 shows a view similar to Fig. 9, the cam of the switching mechanism in its position immediately before the switching member is snapped to its circuit-closing position.

Figs. 13 and 14 are detail views of the cam of the switching mechanism, and are respectively a front elevation and a side view thereof, and

Figs. 15 and 16 are detail views of the switching member of the switching mechanism, being respectively a front elevation and a side elevation thereof.

Similar numerals refer to similar parts throughout the several views.

As shown in Figs. 1—6 inclusive, the socket construction includes a base 10 of suitable insulating material such as porcelain, Bakelite or the like, having a cylindrical bore containing a tubular member 11 of thin sheet metal which is threaded to engage the corresponding threads on the sleeve contacts of lamp bulbs to be used with the socket construction. The tubular member 11 is secured to the base 10 by rivets 12 and 13. The base 10 is provided at the bottom of the bore containing the member 11, with a central rivet 14 electrically connected with a contact member 15 extending to a terminal and binding post 15a contained in a recess 10a in the base 10 (Figs. 1 and 3). The base 10 is provided with a second side recess 10b (Figs. 1, 4 and 6) containing the switching mechanism of the structure.

As more clearly shown in Figs. 9—12 inclusive, the switching mechanism of the socket construction includes a cam 16 of suitable material, for example metal or insulating material, and a switching member 17 together with switch contacts 18 and 19 mounted on the lower end of the base 10 for electrical engagement with a contact block 17a of the switching member 17 when the latter is in its lowermost position indicated in Figs. 9 and 10. The cam 16 is substantially cylindrical for cooperation with opposite cam points 17b, 17b of the switching member 17. The switching member 17 is of thin spring metal and is in the general form of a U (Figs. 15 and 16), so that its upper ends may move towards each other by its spring action, or be separated by the action of the cam 16, the lower mid-portion of said switching member having secured thereto the contact block 17a. The recess 10b is provided with a further recess 10c for the block 17a for engagement with the end of said block, when said switching member is

raised by movement of the cam 16 below the cam points 17b, 17b of the switching member, at which time the spring action of the member 17 causes movement upwardly of the said member, until the contact block 17a is in contact with the upper end of the recess 10c. When the cam 16 is raised above the cam points 17b, 17b, the spring action of the switch member 17 holds the contact block 17a down in firm electrical contact with the switch contacts 18 and 19.

With the switching member 17 in its lower position closing the socket circuit to the lamp bulb as shown in Fig. 9, when the cam 16 is moved downwardly until it just passes the cam points 17b, 17b of the switching member 17, (Fig. 10), the spring action of the member 17 immediately snaps said member upwardly and at the same time moves the cam downwardly and holds said cam in a lower position, the cooperation between the cam and the spring member 17 at that time holding the switching member in its upper position shown in Fig. 11, for which the circuit to the lamp bulb is open. It will thus be seen that movement of the cam 16 upwardly serves to move the switching member 17 downwardly, and that movement of the cam 16 downwardly serves to move the switching member 17 upwardly, or in other words, to close the socket circuit, the cam 16 is moved upwardly and to open the socket circuit, the cam 16 is moved downwardly, for the relation of the parts shown in Figs. 9—12 inclusive. The side walls of the recess 10b serve as guideways for the switching member 17, said side walls being sufficiently spaced to permit lateral expansion of said switching member under the action of the cam 16.

The base 10 and the parts secured thereto, as well as the switching mechanism carried by the base, are enclosed first by a tubular sleeve 20 of insulating material (Fig. 4), and then by a shell 21 of thin metal around said sleeve, which shell is extended below the base 10 to form the necessary compartment for making connection between the socket terminals and the electric conductors used to supply current to the socket. The lower end of the shell 21 is formed inwardly and upwardly and threaded as shown at 21a (Fig. 4), to mount the socket structure on any desired support. A perforated disc 22 of insulating material is preferably disposed in the lower portion of the shell 21 to prevent contact between said shell and the electric conductors used in connecting the socket terminals with the supply circuit.

The cam 16 has threaded engagement with a screw 23 which is permanently a part of a button 24 mounted outside of the shell 21, preferably by molding the material of the button around said screw, (Fig. 4), so that the cam 16 may be moved as above described by corresponding movement of the button 24. The button 24 is provided with a shouldered portion 24a (Fig. 4) which passes through a corresponding slot 25 (Fig. 6) in the sleeve 20 and a similar slot in the shell 21. Movement of the button 24 upwardly relatively to the shell 21 is limited by the recess 10b, and movement downwardly of said button is limited by the slot 25. The cam 16 is secured to a shield portion 16a (Figs. 13 and 14) preferably of insulating material covering the recess 10b and also the slot 25 for different positions of the cam relatively to the base 10. The shield 16a is contained in a shallow recess 10 in the base 10, the side edges of said recess forming guideways for said shield during movement of the latter with the cam 16.

The switch contact 19 is electrically connected by the rivet 13 with the tubular member 11 (Figs. 1 and 8), and the switch contact 18 is extended along the bottom of the base 10 and is integrally a part of the terminal and binding post 26 contained in a side recess 10e in the base 10, said switch contact 18 having an extension 18a by which the contact is rigidly secured to the base by means of a rivet 27 (Figs. 1, 7 and 8).

The base 10 is held in place in the shell 21 by 10 means of an inwardly extending formed lug 21b engaging a bayonet groove 10f in the side of the base 10 (Figs. 4 and 5).

The socket construction described, reduces the height of the structure to that required for receiving and supporting a lamp bulb and for connecting the socket terminals with electric supply conductors. This is a marked advantage where it is desired to use switch sockets with small lamp standards such as boudoir lamps, because of detracting but little if at all from the effect of the designs of such standards, and because of keeping the lamp bulbs in a low position relatively to the standards, both of which effects are of the greatest importance in connection with portable electric lamps. At the same time, the switching mechanism of the invention is of simple and inexpensive construction, free from complication, and most effective in operation.

While I have shown my invention in the particular embodiment described, I do not limit myself thereto as I may employ equivalents thereof without departing from the scope of the appended claims.

Having thus described my invention, what I 35 claim is:

1. A switch socket including in combination a base of insulating material having an end recess for receiving and supporting a lamp bulb having electric terminals, said base having a first side 40 recess for switching mechanism, a cam mounted in said first side recess for reciprocatory movement axially of said socket, a switching member in said first side recess and having a projection pressing against said cam and restricted to reciprocatory movement axially of said socket, said first side recess opening outwardly through the side of said base and also axially through the end of said base remote from its said end recess, switch contacts spaced from each other and mounted on the said remote end of said base and ending in line with said first side recess, the inter-engaging portions of said cam and of said switching member effecting axial movement of said switching member in a direction opposite to the direction of axial movement of said cam, a removable casing surrounding said base, an operating button outside of said casing and connected with said cam, said casing having an axial slot therethrough for receiving said button connection, said base having electric contacts for engaging said bulb terminals, and socket terminals in additional side recesses in said base spaced from each other and from said first side recess, said switch contacts having electrical connection with one of said base contacts and with one of said socket terminals respectively, and the other of said socket terminals having electrical connection with the other of said base contacts, said switching member in one of its positions electrically connecting said switch contacts and by movement to its other position breaking electrical connection between said switch contacts.

2. A switch socket including in combination a base of insulating material having an end recess

for receiving and supporting a lamp bulb having electric terminals, said base having a first side recess for switching mechanism, a cam mounted in said first side recess for reciprocatory movement axially of said socket, a switching member in said first side recess and having a projection pressing against said cam and restricted to reciprocatory movement axially of said socket, said first side recess opening outwardly through the side of said base and also axially through the end of said base remote from its said end recess, switch contacts spaced from each other and mounted on the said remote end of said base and ending in line with said first side recess, the inter-engaging portions of said cam and of said switching member effecting axial movement of said switching member in a direction opposite to the direction of axial movement of said cam, a removable casing surrounding said base, an operating button outside of said casing and connected with said cam, said casing having an axial slot therethrough for receiving said button connection, said base having electric contacts for engaging said bulb terminals, socket terminals in additional side recesses in said base spaced from each other and from said first side recess, said switch contacts having electrical connection with one of said base contacts and with one of said socket terminals respectively, and the other of said socket terminals having electrical connection with the other of said base contacts, said switching member in one of its positions electrically connecting said switch contacts and by movement to its other position breaking electrical connection between said switch contacts, and a shield connected with said cam and covering said slot.

3. A switch socket including in combination a base of insulating material having an end recess for receiving and supporting a lamp bulb having electric terminals, said base having a first side recess for switching mechanism, a cam mounted in said first side recess for reciprocatory movement axially of said socket, a switching member in said first side recess and having a projection pressing against said cam and restricted to reciprocatory movement axially of said socket, said first side recess opening outwardly through the side of said base and also axially through the end of said base remote from its said end recess, switch contacts spaced from each other and mounted on the said remote end of said base and ending in line with said first side recess, the inter-engaging portions of said cam and of said switching member effecting axial movement of said switching member in a direction opposite to the direction of axial movement of said cam, a removable casing surrounding said base, an operating button outside of said casing and connected with said cam, said casing having an axial slot therethrough for receiving said button connection, said base having electric contacts for engaging said bulb terminals, and socket terminals in additional side recesses in said base spaced from each other and from said first side recess, said switch contacts having electrical connection with one of said base contacts and with one of said socket terminals respectively, and the other of said socket terminals having electrical connection with the other of said base contacts, said switching member in one of its positions electrically connecting said switch contacts and by movement to its other position breaking electrical connection between said switch contacts, said switching member having opposite portions press-

ing with equal forces against opposite sides of said cam.

4. A switch socket including in combination a base of insulating material having an end recess for receiving and supporting a lamp bulb having electric terminals, said base having a first side recess for switching mechanism, a cam mounted in said first side recess for reciprocatory movement axially of said socket, a switching member in said first side recess and having a projection pressing against said cam and restricted to reciprocatory movement axially of said socket, said first side recess opening outwardly through the side of said base and also axially through the end of said base remote from its said end recess, switch contacts spaced from each other and mounted on the said remote end of said base and ending in line with said first side recess, the interengaging portions of said cam and of said switching member effecting axial movement of said switching member in a direction opposite to the direction of axial movement of said cam, a removable casing surrounding said base, an operating button outside of said casing and connected with said cam, said casing having an axial slot therethrough for receiving said button connection, said base having electric contacts for engaging said bulb terminals, and socket terminals in additional side recesses in said base spaced from each other and from said first side recess, said switch contacts having electrical connection with one of said base contacts and with one of said socket terminals respectively, and the other of said socket terminals having electrical connection with the other of said base contacts, said switching member in one of its positions electrically connecting said switch contacts and by movement to its other position breaking electrical connection between said switch contacts, said switching member having opposite portions provided with similar projections extending towards each other, and said cam having opposite cam surfaces for engaging said switching member projections.

5. A switch socket including in combination a base of insulating material having an end recess for receiving and supporting a lamp bulb having electric terminals, said base having a first side recess for switching mechanism, a cam mounted in said first side recess for reciprocatory movement axially of said socket, a switching member in said first side recess and having a projection pressing against said cam and restricted to reciprocatory movement axially of said socket, said first side recess opening outwardly through the side of said base and also axially through the end of said base remote from its said end recess, switch contacts spaced from each other and mounted on the said remote end of said base and ending in line with said first side recess, the interengaging portions of said cam and of said switching member effecting axial movement of said switching member in a direction opposite to the direction of axial movement of said cam, a removable casing surrounding said base, an operating button outside of said casing and connected with said cam, said casing having an axial slot therethrough for receiving said button connection, said base having electric contacts for engaging said bulb terminals, and socket terminals in additional side recesses in said base spaced from each other and from said first side recess, said switch contacts having electrical connection with one of said base contacts and with one of said socket terminals respectively, and the other of said socket terminals having electrical connection with the other of said base contacts, said switching member in one of its positions electrically connecting said switch contacts and by movement to its other position breaking electrical connection between said switch contacts, said switching member having opposite portions provided with similar projections extending towards each other, and said cam having opposite cam surfaces for engaging said switching member projections.

5. A switch socket including in combination a base of insulating material having an end recess for receiving and supporting a lamp bulb having electric terminals, said base having a first side recess for switching mechanism, a cam mounted in said first side recess for reciprocatory movement axially of said socket, a switching member in one of its positions electrically connecting said switch contacts and by movement to its other position breaking electrical connection between said switch contacts, said casing extending around said remote end of said base with an end clearance restricted to that required for electric supply conductors connected with said socket terminals.

10. A switch socket including in combination a base of insulating material having an end recess for receiving and supporting a lamp bulb having electric terminals, said base having a first side recess for switching mechanism, a cam mounted in said first side recess for reciprocatory movement axially of said socket, a switching member in said first side recess and having a projection pressing against said cam and restricted to reciprocatory movement axially of said socket, said first side recess opening outwardly through the side of said base and also axially through the end of said base remote from its said end recess, switch contacts spaced from each other and mounted on the said remote end of said base and ending in line with said first side recess, the interengaging portions of said cam and of said switching member effecting axial movement of said switching member in a direction opposite to the direction of axial movement of said cam, a removable casing surrounding said base, an operating button outside of said casing and connected with said cam, said casing having an axial slot therethrough for receiving said button connection, said base having electric contacts for engaging said bulb terminals, and socket terminals in additional side recesses in said base spaced from each other and from said first side recess, said switch contacts having electrical connection with one of said base contacts and with one of said socket terminals respectively, and the other of said socket terminals having electrical connection with the other of said base contacts, said switching member in one of its positions electrically connecting said switch contacts and by movement to its other position breaking electrical connection between said switch contacts, said switching member comprising a metal strip bent into a U shape and a contact block carried by its mid-portion for engaging said switch contacts, said switch member having its side members on opposite sides of and for engagement with said cam.

7. A switch socket including in combination a base of insulating material having an end recess for receiving and supporting a lamp bulb, said base having a side recess for switching mechanism, a cam mounted in said side recess for reciprocatory movement axially of said socket, a switching member in said side recess and having a projection pressing against said cam and restricted to reciprocatory movement axially of said socket, switch contacts spaced from each other and mounted on said base and ending in line with said side recess, the interengaging portions of said cam and of said switching member effecting axial movement of said switching member in a direction opposite to the direction of axial movement of said cam, and an operating button connected with said cam, said switch contacts having electrical connections for controlling current flow through a lamp bulb in said end recess, said switching member in one of its positions electrically connecting said switch contacts and by movement to its other position breaking electrical connection between said switch contacts.

8. A switch socket including in combination a base of insulating material having an end recess for receiving and supporting a lamp bulb, said base having a side recess for switching mechanism, a cam mounted in said side recess for reciprocatory movement axially of said socket, a switching member in said side recess and having a projection pressing against said cam and restricted to reciprocatory movement axially of said socket, switch contacts spaced from each other and mounted on said base and ending in line with said side recess, the interengaging portions of said cam and of said switching member effecting axial movement of said switching member in a direction opposite to the direction of axial movement of said cam, and an operating button connected with said cam, said switch contacts having electrical connections for controlling current flow through a lamp bulb in said end recess, said switching member in one of its positions electrically connecting said switch contacts and by movement to its other position breaking electrical connection between said switch contacts, said switching member having opposite portions pressing with equal forces against opposite sides of said cam.

9. A switch socket including in combination a base of insulating material having an end recess for receiving and supporting a lamp bulb, said base having a side recess for switching mechanism, a cam mounted in said side recess for reciprocatory movement axially of said socket, a switching member in said side recess and having a projection pressing against said cam and restricted to reciprocatory movement axially of said socket, switch contacts spaced from each other and mounted on said base and ending in line with said side recess, the interengaging portions of said cam and of said switching member effecting axial movement of said switching member in a direction opposite to the direction of axial movement of said cam, and an operating button connected with said cam, said switch contacts having electrical connections for controlling current flow through a lamp bulb in said end recess, said switching member in one of its positions electrically connecting said switch contacts and by movement to its other position breaking electrical connection between said switch contacts, said switching member having opposite portions provided with similar projections extending towards each other, and said cam having opposite cam surfaces for engaging said switching member projections.

10. A switch socket including in combination a base of insulating material having an end recess for receiving and supporting a lamp bulb, said base having a side recess for switching mechanism, a cam mounted in said side recess for reciprocatory movement axially of said socket, a switching member in said side recess and having a projection pressing against said cam and restricted to reciprocatory movement axially of said socket, switch contacts spaced from each other and mounted on said base and ending in line with said side recess, the interengaging portions of said cam and of said switching member effecting axial movement of said switching member in a direction opposite to the direction of axial movement of said cam, an operating button connected with said cam, said switch contacts having electrical connections for controlling current flow through a lamp bulb in said end recess, said switching member in one of its positions electrically connecting said switch contacts and by

movement to its other position breaking electrical connection between said switch contacts, and a removable casing around the side and around the end of said base remote from its said end recess and having an end clearance from said remote end restricted to that required for electric supply conductors.

11. A switch socket including in combination a base of insulating material having an end recess for receiving and supporting a lamp bulb, said base having a side recess for switching mechanism, a cam mounted in said side recess for reciprocatory movement axially of said socket, a switching member in said side recess and having a projection pressing against said cam and restricted to reciprocatory movement axially of said socket, switch contacts spaced from each other and mounted on said base and ending in line with said side recess, the interengaging portions of said cam and of said switching member effecting axial movement of said switching member in a direction opposite to the direction of axial movement of said cam, and an operating button connected with said cam, said switch contacts having electrical connections for controlling current flow through a lamp bulb in said end recess, said switching member in one of its positions electrically connecting said switch contacts and by movement to its other position breaking electrical connection between said switch contacts, said switching member comprising a metal strip bent into a U-shape and provided at its mid-portion with a contact block for engaging said switch contacts and having its side members on opposite sides of and in engagement with said cam.

12. Switching mechanism for electric lamp sockets, including in combination a cylindrical base of insulating material having an end recess for a lamp socket and a wall extending laterally at the inner end of said socket recess limited in thickness to that required for mounting a lamp socket in said socket recess, the axial length of said base being limited to the combined axial length of said socket recess and the thickness of said end wall, said base also having a side recess opening laterally through the side of said base, spaced switch contacts in line with said side recess, a switching member contained in said side recess and movable therein to electrically connect and electrically separate said switch contacts as desired, and a cam contained in said side recess and movable therein to operate said switching member, said switching member having opposite portions provided with similar projections extending towards each other, and said cam having opposite cam surfaces for engaging said switching member projections.

13. Switching mechanism for electric lamp sockets, including in combination a cylindrical base of insulating material having an end recess for a lamp socket and a wall extending laterally at the inner end of said socket recess limited in thickness to that required for mounting a lamp socket in said socket recess, the axial length of said base being limited to the combined axial length of said socket recess and the thickness of said end wall, said base also having a side recess opening laterally through the side of said base, spaced switch contacts in line with said side recess, a switching member contained in said side recess and movable therein to electrically connect and electrically separate said switch contacts as desired, and a cam contained in said side recess and movable therein to operate said switching member, said switching member comprising a

metal strip bent into a U shape and provided at its mid-portion with a contact block for engaging said switch contacts and having its side members on opposite sides of and in engagement with said cam.

14. Switching mechanism for electric lamp sockets, including in combination a cylindrical base of insulating material having an end recess for a lamp socket and a wall extending laterally at the inner end of said socket recess limited in thickness to that required for mounting a lamp socket in said socket recess, the axial length of said base being limited to the combined axial length of said socket recess and the thickness of said end wall, said base also having a side recess opening laterally through the side of said base, spaced switch contacts in line with said side recess, a switching member contained in said side recess and movable therein to electrically connect and electrically separate said switch contacts as desired, and a cam contained in said side recess and movable therein to operate said switching member, said switching member comprising a strip of thin spring metal bent to engage opposite sides of said cam with equal pressures and provided with a contact block to cooperate with said switch contacts.

15. Switching mechanism for electric lamp sockets, including in combination a cylindrical base of insulating material having an end recess for a lamp socket and a wall extending laterally at the inner end of said socket recess limited in thickness to that required for mounting a lamp socket in said socket recess, the axial length of said base being limited to the combined axial length of said socket recess and the thickness of said end wall, said base also having a side recess opening laterally through the side of said base, spaced switch contacts in line with said side recess, a switching member contained in said side recess and movable therein to electrically connect and electrically separate said switch contacts as desired, and a cam contained in said side recess and movable therein to operate said switching member, said switching member comprising a strip of thin spring metal bent to engage opposite sides of said cam with equal pressures and provided with a contact block to cooperate with said switch contacts, said switching member being free from connection with said base and with said cam

and being limited in its movement solely by said cam, by the walls of said side recess and by said switch contacts.

16. Switching mechanism for electric lamp sockets, including in combination a cylindrical base of insulating material having an end recess for a lamp socket and a wall extending laterally at the inner end of said socket recess limited in thickness to that required for mounting a lamp socket in said socket recess, the axial length of said base being limited to the combined axial length of said socket recess and the thickness of said end wall, said base also having a side recess opening laterally through the side of said base, spaced switch contacts in line with said side recess, a switching member contained in said side recess and movable therein to electrically connect and electrically separate said switch contacts as desired, and a cam contained in said side recess and movable therein to operate said switching member, said switching member being free from connection with said base and with said cam and being limited in its movement solely by said cam, by the walls of said side recess and by said switch contacts.

17. Switching mechanism for electric lamp sockets, including in combination a cylindrical base of insulating material having an end recess for a lamp socket and a wall extending laterally at the inner end of said socket recess limited in thickness to that required for mounting a lamp socket in said socket recess, the axial length of said base being limited to the combined axial length of said socket recess and the thickness of said end wall, said base also having a side recess opening laterally through the side of said base, spaced switch contacts in line with said side recess, a switching member contained in said side recess and movable therein to electrically connect and electrically separate said switch contacts as desired, and a cam contained in said side recess and movable therein to operate said switching member, said switching member and said cam being limited to reciprocatory movement towards and from said switch contacts, said switching member and said cam having cooperating engaging surfaces moving said switching member in a direction opposite to the direction of movement of said cam.
